VENDING MACHINE

Louis Bonaccolta and Jacob Noddleman, Houston,
Tex., assignors to Automatic Cabinets, Inc.,
Houston, Tex., a corporation of Texas

Application May 19, 1932, Serial No. 612,229

1 Claim. (Cl. 312—67)

This invention relates to a vending machine.

An object of the invention is to provide a machine specially designed to dispense individual objects, such as individual quantities of ice cream 5 and the like.

Another object is to provide a machine of the character described wherein novel means are provided for storing the articles to be vended, as well as novel ejecting means whereby the articles 10 may be ejected singly for access to the purchaser.

With the above and other objects in view this invention has particular relation to certain novel features of construction, operation and arrangement of parts an example of which is given in 15 this specification and illustrated in the accompanying drawings, wherein:—

Figure 1 shows a front elevation of the machine.

Figure 2 shows a cross sectional view taken on the line 2—2 of Figure 4.

20 Figure 3 shows a fragmentary vertical sectional view taken on the line 3—3 of Figure 4.

Figure 4 shows a vertical sectional view of the complete machine.

Figure 5 shows a side elevation of a skeleton 25 carton employed and

Figure 6 shows a plan view of a coin controlled mechanism employed.

Referring now more particularly to the drawings wherein like numerals of reference designate 30 similar parts in each of the figures the numeral 1 designates the casing which should be formed of relatively thick walls and which is provided with a removable rear panel 2. This casing is provided with one or more vertical storage chambers 3, 3, 3, for containing the articles of merchandise such as blocks of ice cream and the like which are to be sold. The storage chambers 35 are preferably provided with a metallic lining as 4 and each chamber is of the required cross sectional contour to receive snugly the articles of merchandise. There is, preferably, a plurality of storage chambers so that articles of different flavors may be stored in such manner that the desired flavor may be selected by the purchaser.

40 In actual practice, the articles to be inserted into the storage chambers, will be assembled in a skeleton like carton 5. These skeletons, when filled with the merchandise, will then be inserted into the chambers and may be removed for reuse 45 when emptied, if desired.

In front of the merchandise chambers 3 and extending entirely across the machine, there is a downwardly tapering ice chamber 6 provided to contain crushed ice and whose bottom is 50 formed of foraminated material.

Beneath the storage chambers 3 there is a downwardly and forwardly declining discharge chute 7 whose forward end is closed by the doors 8, 8, 8, which are normally held closed by springs 9 and which are provided with suitable grips 60 10 by means of which they may be opened.

There is a plunger 11 behind the bottom article 12 of each storage space, said plungers 11 being operable in the transverse guideways 13 provided for the purpose. Each plunger is connected to 65 the upper end of a lever 14 by means of the upper push bar 15. There is a lower push bar 16 whose inner end is connected to the lower end of each lever 14 and the outer end of this lower push bar is accessible in front of the machine and has a suitable knob 17 thereon. Each push bar 16 is provided with a slip joint as 16' 70 so that it will operate more freely. Each lever 14 is pivoted at an intermediate point on a rearwardly extending arm 18 and these arms are 75 fixed to a suitable cross rod 19 whose ends rotate in bearings in the respective side walls of the casing.

When a push bar 16 is forced inwardly the corresponding plunger 11 will be moved outwardly 80 and will discharge the article in front of it into the chute 7 and said article will pass down the chute 7 and will be stopped by the corresponding door 8 and said door may be opened and the article of merchandise may be obtained. 85

There is an open space 20 beneath the ice chamber 6 through which the water collecting in the chamber 6 may drip into the chute 7 to keep the same cool and the air, thus cooled in the chute 7 may circulate up about the articles 90 in the storage chambers.

A push bar 16 can not be operated until a coin of the required denomination be inserted into a coin controlled mechanism associated with said push bar and designated generally by the numeral 21. This coin controlled mechanism is of conventional construction and forms no part of the present invention and for that reason will not be described specifically in detail.

The storage chambers and ice chamber are 100 closed at the top by a suitable door or shutter 22 forming a portion of the top of the casing 1.

Across the lower portion of the casing in front there is a transparent window 23 provided for the purpose of inspecting the storage chambers to ascertain whether or not they are supplied with merchandise. 105

On each tier of articles there is a block 24, preferably of wood of such thickness that it will 110 not pass out through the discharge opening at

the bottom of the corresponding chamber, and provided for locking the corresponding coin controlled mechanism 21 when said chamber 3 is emptied.

5 The drawings and description disclose what is now considered to be a preferred form of the invention by way of illustration only while the broad principle of the invention will be defined by the appended claim.

What we claim is:

10 A vending machine including a casing having a storage chamber therein shaped to snugly receive articles of merchandise of similar dimensions and to feed said articles downwardly by gravity, said casing having a forwardly declin-

15 ing chute leading from the bottom of said cham-

ber, a plunger arranged to move transversely across the lower end of said chamber, a rod in in and extending across the casing, an arm on said rod and swingable in a plane at right angles to said rod, a lever pivoted, at an intermediate point, to said arm and freely movable on said pivot and also freely movable vertically in a plane at right angles to said rod, a push bar to one end of which said plunger is attached and whose other end is pivoted to one end of said lever, a push bar pivoted at its inner end to the other end of the lever and whose other end is accessible to an operator.
